UNITED STATES PATENT OFFICE.

JOHN H. KENNETH AND FREDERICK N. WAFFLE, OF PHILADELPHIA, PENNSYLVANIA.

DESIGN FOR AN INHALER.

56,560.

Specification for Design.

Patented Nov. 9, 1920.

Application filed October 14, 1919. Serial No. 330,812. Term of patent 7 years.

To all whom it may concern:

Be it known that we, JOHN H. KENNETH and FREDERICK N. WAFFLE, citizens of the United States, residing at Philadelphia, in the county of Philadelphia and State of Pennsylvania, have invented a new, original, and ornamental Design for an Inhaler, of which the following is a specification, reference being had to the accompanying drawing, forming a part thereof.

The figure is a perspective view showing our design.

We claim:

The ornamental design for an inhaler as shown.

JOHN H. KENNETH.
FREDERICK N. WAFFLE.
